ELASTIC FABRIC

Filed June 19, 1923

Inventor-
George F. Townsend
by his Attorneys-
Brown & Brown.

UNITED STATES PATENT OFFICE.

GEORGE F. TOWNSEND, OF PHILADELPHIA, PENNSYLVANIA, ASSIGNOR OF ONE-HALF
TO EARL WHEELER JENKINS, OF PHILADELPHIA, PENNSYLVANIA.

ELASTIC FABRIC.

Application filed June 19, 1923. Serial No. 646,456.

My invention relates to elastic fabrics of the type including rubber or similar strands, and the object of the invention is to provide a novel fabric of this type possessing the 5 advantages hereinafter set forth.

In the attached drawings:

Figure 1, is a face view of a fragment of fabric made in accordance with my invention, and

10 Fig. 2, is a section on the line 2—2 of Fig. 1.

With reference to the drawings, I have therein illustrated a warp knit fabric employing the nubia stitch. Although it is to be understood that the invention in its broadest aspect is not limited to any particular type of fabric, warp knit fabrics and particularly fabrics employing the nubia and like stitches are particularly well adapted 20 for the purposes of the invention.

The fabric illustrated in the drawings, as is well understood by those familiar with the knitting art, is practically non-extensible in a weftwise direction, while extremely so 25 in the direction of the warps. As clearly illustrated, the loops of the nubia stitches arrange themselves in rows running longitudinally of the fabric or with the warps, the alternate loops of each thread in the present 30 instance occupying adjacent rows. Thus I have designated in Figure 1 of the drawings the left-hand loops of each thread as 1, and the right-hand loops 2, the said loops 1 of one thread interlocking with the right-hand 35 loops, 2, of the adjacent thread.

Intermediate the said rows of loops and extending across one side of the fabric parallel to said rows is a rubber strand 3, which latter is tied in on the fabric by means of 40 an inlay thread 4 which interlaces with the stitches of the fabric intermediate the said rows of loops, said thread 4 passing back and forth over the said rubber strand 3, as clearly illustrated. It will be noted that the strands 45 of rubber 3 extend without distortion in the direction of the warps which, as previously stated, is the direction in which the said fabric is extensible, and the rubber has the effect of tending to retain the fabric in the 50 normal unstretched condition and returning the fabric to such condition after it has been extended. As shown in the drawing, the

strands of rubber 3 are laid against the body of the fabric without being knitted thereto, the threads making up the body of the 55 fabric engaging the strands of rubber for a portion only of the peripheral or angular extent of the latter. The inlay or tying threads likewise extend only part way around the peripheries of the strands of rubber although when interlocked the tying threads and the threads of the body of the fabric together completely encircle the strands of rubber. As the threads of the 60 body of the fabric and the tying threads engage opposed portions of the strands of rubber and are interlaced adjacent opposed portions thereof and as neither the threads of the body of the fabric nor the tying threads individually or separately encircle or 65 coil about the strands of rubber they do not laterally stretch or distort the same from their normal straight form.

To give the fabric more body and strength, I may interweave with the threads which 75 form the loops 1 and 2 a reinforcing thread 5 which follows the general course of the loops 1 and 2 of each of the said rows.

In elastic fabrics of this nature, it has been customary, prior to my invention, to 80 extend the rubber strands weftwise, and so far as I am aware, I am the first to provide a knit fabric in which the rubber strands extend with the warps.

The advantages are several, the most important being a greatly increased production 85 over fabrics of this general type in which the rubber extends weftwise and the fact that I am able to provide by use of the nubia and such open network stitches a 90 comparatively open fabric which adds greatly to the value of the product by reason of comparative coolness when worn. I am further able to provide the fabric with various ornamental stitches, making it suitable 95 for purposes for which the previous fabrics of this nature are unadapted, and I have found that my fabric in appearance conforms more nearly to the ordinary knit fabrics than do other fabrics comprising 100 rubber strands.

Although, as illustrative of the invention, I have shown and described a fabric made up of a particular stitch, it will be under-

stood that the invention is not limited thereby, but applies in its broader sense to any type of fabric which is extensible in the direction of the warps and which includes 5 the rubber strands.

I claim:

1. A knitted fabric having a body made up of interlaced threads, rubber strands extending along and lying flatly against certain of the threads of the body and tying threads interlaced with, though separate from and independent of the threads of the body of the fabric and engaged with portions of the rubber strands opposed to the
- 10

portions of such strands engaged with the 15 fabric body.

2. A warp knit fabric in which alternate loops of each thread form different rows, a strand of rubber lying against the fabric intermediate and paralleling said rows, the 20 fabric engaging a portion only of each strand and extending only partly around the same, and threads interlacing with the said looped threads intermediate the rows of loops and extending partly around and engaging portions only of said strands. 25

GEORGE F. TOWNSEND.
